Primary Examiner — Kimberly Barnes(74) *Attorney, Agent, or Firm* — Kolitch Romano LLP(57) **CLAIM**

The ornamental design for a helmet, as shown and described.

DESCRIPTION

FIG. 1 is a front, right, and top perspective view of a helmet embodying the new design;

FIG. 2 is a rear, right, and bottom perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.

The broken lines in the figures are shown for the purpose of illustrating portions of the helmet that form no part of the claimed design.
